SLIDING JAW SCREW CAP REMOVER

Franz K. Krag, Chicago, Ill., assignor to Krag Steel Products, Inc., Chicago, Ill., a corporation of Illinois

Application January 24, 1952, Serial No. 267,943

2 Claims. (Cl. 81—3.42)

1

This invention relates to improvements in jar openers, and the like. These implements are used in connection with the opening of jars, generally for household uses, and these implements provide means to secure a very firm hold on the jar cover to start the unscrewing of the same from the jar. They may also be used for tightening the covers when closing the jars.

Generally speaking, the present improvements relate to that form of jar opener shown in Letters Patent of the United States No. 2,000,962, issued on my application May 14, 1935. In that form of jar opener there is provided a frame which includes two parallel rails or rods along which a gripping jaw device may be slid and forced towards a companion stationary jaw element. The slideable jaw device is so formed that it may be freely moved along the rails to bring its jaw member into gripping engagement with the jar cover at a location opposite to a position of engagement of the stationary jaw element. The slideable jaw device is also provided, in that patent, with a hand grip which, when rocked towards the adjacent frame rail serves to force the movable jaw member into strong engagement and pressure against the jar cover, thus gripping the jar cover between the stationary and movable jaw members with a force which is proportionate to the force with which the hand grip element is forced towards the frame rail.

In the construction shown in that earlier patent I have provided a dog or pawl which is pivoted to the hand grip at a point between the two frame rails, and this dog or pawl is provided with a tooth which may be engaged with one of the teeth formed along the inwardly facing surface of one of the frame rails. Such engagement must be effected by rocking the hand grip slightly in the jar gripping direction; and after such engagement of the pawl with a tooth of the rail, further rocking of the hand grip under increasing force will cause the movable jaw device to be gripped with a corresponding force against the jar cover. The movement which may be caused by rocking of the hand grip after the pawl has been engaged with a tooth of the frame rail is sufficient to ensure strong gripping engagement with the jar cover, but is not sufficient to accommodate jar covers of different sizes; nor is such movement sufficient to enable convenient placement of the jar opener over the jar cover, except by the exercise of considerable care. Accordingly, the parts are so proportioned that by rocking the hand grip away from its gripping position the pawl will be completely disengaged from the teeth of the frame

2

rail, so that the gripping jaw device may be readily and freely slid along the rails to bring the two opposing jaws into preliminary engagement with the opposite portions of the jar cover. Having done this the hand grip element serves to develop whatever amount of gripping force may be desired to hold the jar cover securely during the starting of unscrewing such cover.

It is also to be noted that when the hand grip of that earlier construction has once been forced close to the adjacent frame rail, and with the pawl in engagement with one of the rail teeth, it is not possible to move the parts back along the rails for separating the two jaws from each other, except by taking hold of the hand grip element and purposely rocking it outwardly away from the frame rail to which it had been moved. Furthermore, when it is desired to again use the device for a cover gripping operation, it is necessary for the user to purposely rock the hand grip still further from the adjacent frame rail in order to bring the pawl into position such that another engaging operation of such pawl with the teeth may be produced, as needed to produce another jar cover gripping operation.

The principal object of the present invention is to provide, in jar cover removers of the general type of that earlier patent, spring means acting in connection with the hand grip, and in connection with the pawl, to normally urge the hand grip outwardly into disengaged or inoperative position, so that said part will normally stand in position ready for another cover removing operation; and to also provide spring means between the hand grip and the pawl normally urging the pawl towards tooth engagement with the frame rail, so that it is not necessary at any time for the user to produce a special movement or adjustment in order to bring the pawl into such tooth engagement; but it is also an important feature in connection with the foregoing features to provide means to limit the movement of the pawl with respect to the hand grip, in the tooth engaging direction, so that when the hand grip is normally and fully spring moved in its disengaging direction the pawl will be drawn away from the teeth of the frame rail, even against the urging of the spring which urges said pawl towards engagement with said rail teeth. It is then an object to so arrange the parts that when gripping movement of the hand grip is commenced towards the adjacent frame rail the pawl will move with such hand grip, as the hand grip is thus moved against its spring urging, to carry the pawl tooth into engagement with a rail tooth; and it is a

further object to so arrange the spring means that when the foregoing condition has been attained, further rocking of the hand grip, against the urging of its spring means, will cause the desired cover gripping action to occur, the pawl's tooth being retained firmly in engagement with a rail tooth during this operation by reason of the urging of the spring means which acts on the pawl.

In connection with the foregoing, it is a further object of the present invention to so arrange the spring means for both the hand grip and the pawl, that when one gripping operation has been completed, with consequent forcing of the hand grip into limiting movement engagement with the adjacent frame rail, and with corresponding maximum pawl movement in its force producing direction, another cover gripping movement of the parts may be produced to carry the movable jaw element to a further position in its cover gripping direction, the carriage which travels on the frame rails remaining in its most forwardly moved position, and the pawl now being advanced to position to engage another tooth of the frame rail, closer to the stationary jaw than the previously engaged tooth. By this means it is possible, if necessary, to force the movable jaw towards the stationary jaw element with two or even three distinct steps of gripping engagement movement, and without need of special adjustments or re-engagements of parts by the user.

A further feature and object of the invention is to provide the spring actions above referred to by use of a single spring element, so arranged, and so engaged with the parts that it is capable of producing the proper reactions, and producing the desired relative urgings and movements of the parts.

It is a further feature and object of the invention to so arrange the spring element, and to so produce the desired reactions, that such spring element may be introduced into and combined with standard forms and constructions of jar cover openers which have been made and are currently being made according to the teachings of said earlier patent, and substantially without need of redesign or change of the dies and other manufacturing equipment and operations used in connection with large scale manufacture of the jar openers made according to that earlier patent. Thus, the present improvements may be readily adapted into and used in connection with such manufacturing equipment and designs now currently in use.

Other objects and uses of the invention will appear from a detailed description of the same which consists in the features of construction and combinations of parts hereinafter described and claimed.

In the drawing:

Figure 1 shows a plan or face view of a typical jar cover opener embodying the features of the present invention, and with the hand grip in its normally spring retracted and disengaged position, with the pawl also fully disengaged and slightly removed back away from the frame rail teeth, this figure being on substantially full scale of a typical unit;

Figure 2 shows, on enlarged scale as compared to Figure 1, a planar section through the carriage element, and various of the parts, the hand grip being in its normally fully spring retracted position, and the pawl also being drawn back slightly away from the frame rail teeth;

Figure 3 shows another section similar to that

of Figure 2, but with the hand grip rocked somewhat towards the adjacent frame rail, far enough to carry the pawl tooth almost into engagement with one of the frame rail teeth; and in this figure the spring element which urges the hand grip into its disengaging position has been slightly deformed, but the spring element which normally urges the pawl tooth into engagement with one of the frame rail teeth has not yet been deformed from its original or previous form and tension, although said spring element constantly urges the pawl to rock with respect to the hand grip and in direction which, if permitted, would carry the pawl into tooth engagement with the frame rail tooth;

Figure 4 shows another section similar to the sections of Figures 2 and 3; but in Figure 4 the hand grip has been forced fully in the jar cover gripping direction, against the urging of the hand grip spring element; and correspondingly the pawl has been further moved to carry its tooth into engagement with one of the frame rail teeth, and then the further rocking movement of the hand grip has caused the pivotal point of the pawl to be forced towards the stationary jaw element, due to the relative positions and relationships of the pivotal points of the hand grip on the carriage, and of the pawl on the hand grip, according to the teachings of said earlier patent; but in Figure 4 these movements and operations have also caused deformation of the pawl spring as well as the hand grip spring, and under the conditions existing as shown in Figure 4 any relaxation of the gripping force on the hand grip, sufficient to allow said hand grip to swing outwardly from the adjacent frame rail would cause the pawl to be drawn towards the observer, that is, towards the stationary jaw member, on the assumption that the carriage were held against backward movement along the frame rails at such time;

Figure 5 shows a longitudinal section taken on the line 5—5 of Figure 4, looking in the direction of the arrows, but with the insert of Figures 8 and 9 secured to the carriage, said insert being shown in face view in Figure 8;

Figure 6 shows a transverse longitudinal section taken on the line 6—6 of Figure 4, looking in the direction of the arrows, being in effect an edge view looking at the assembly which includes the hand grip, and the pawl element, together with the spring element to which the present improvements especially relate;

Figure 7 shows a fragmentary section taken on the line 7—7 of Figure 1, looking in the direction of the arrows, but on enlarged scale, and it also shows the insert for the lower stationary jaw member in place;

Figure 8 shows a detail face view of the insert for the carriage jaw, prior to inserting the same into place on said jaw; and

Figure 9 shows an edge view of the insert for the carriage jaw, being an edge view corresponding to Figure 8.

In the figures the frame rails are shown at 10 and 11. Conveniently they comprise the arms of a U-shaped element of rod material. A cross member 12 is secured to the free ends of said arms, said cross member being provided with an off-set flange 13 which has the serrated edge 14 facing towards the closed end of the frame member. A carriage element 15 has its side edges 16 and 17 folded around the arms 10 and 11, so that said carriage may slide back and forth on the arms or rails. The central portion of this car-

riage is provided with the off-set flange 18 which is provided with the serrated edge 19 which lies in the same plane with the serrated edge 14, said plane being off-set from the plane of the rails 10 and 11. These two serrated edges grip the jar cover flange between them during a cover removing (or replacing) operation.

A hand grip element 20 is provided, such hand grip conveniently comprising a blank of sheet metal formed to provide the spaced upper and lower flanges 21 and 22. These flanges are separated sufficiently to receive one of the rails 11 between them as well shown in various of the figures. The lower or inner ends of these flanges 21 and 22 are formed to provide the lugs 23 and 24. A bracket element 25 is provided, being of Z from, including the ear 26 on its lower end, and the lug 27 on its upper end. The central portion of the carriage is perforated as shown at 28, and is also formed upwardly an amount substantially equal to the thickness of the ear 26, at a position adjacent to such perforation 28. Thus the ear may be set down through the perforation and locked in place against such upwardly formed portion, as well shown in Figure 5 in particular. The lug 27 of the bracket element 25 is then located at an elevation to set against the inside face of the lug 23 of the hand grip when the parts are assembled. When thus assembled the other lug 24 of the hand grip element seats against the lower and outer face of the carriage element. A pivot rivet 29 is extended through both of the lugs 23 and 24 of the hand grip element, and through the bracket lug 27 and the carriage element, as well shown in Figure 5 and others.

The pawl element 30 is of U-shaped form, including the parallel flanges 31 and 32. These side flanges are separated from each other an amount sufficient to permit the pawl element to set between the lugs 23 and 24 of the hand grip element, as well shown especially in Figures 5 and 6. This pawl element also includes the top connecting portion 33 which joins the flanges 31 and 32. The right-hand end portion 34 of this portion 33 projects slightly beyond the flanges to provide a sharpened edge which may engage with the various serrations or teeth 35 formed on the inwardly facing surface of the rail or arm 10, when the pawl element is shifted rightwardly to a position just beyond the position shown in Figure 3. The left-hand end portion 36 of the connecting portion 33 of the pawl projects slightly leftward beyond the flanges 31 and 32 to provide an abutment which will engage the rail or arm 11 when the pawl element is shifted leftwardly to a position as shown in Figure 2. A rivet 37 is extended through both of the lugs 23 and 24 of the hand grip element and through the flanges 31 and 32 of the pawl element, as well shown in Figures 5 and 6.

With the structures thus far described it is evident that when the carriage and the hand grip are in the position shown in Figure 2 the carriage may be freely moved along the rails in either direction since the pawl clears the teeth or serrations of the rail 10 at all times; that when the hand grip is rocked to the position shown in Figure 3 the pawl edge 34 is just ready to engage the teeth or serrations when the hand grip is rocked rightwardly slightly more than shown in that figure so as to produce driving engagement between the pawl and the rail 10; and that when the hand grip has been rocked fully to the right as shown in Figure 4 the pawl edge 34 has engaged one of

the teeth or serrations, and due to the relative pivotal positions of the rivets 29 and 37 a toggle action is produced such that the carriage is forced towards the stationary jar cover engaging edge 14 by the amount of distance shown at 38 in Figure 4. When the carriage position of Figure 4 has been attained the pawl element is rocked counterclockwise its full amount. By then rocking the hand grip counterclockwise a time will come when the left-hand edge 36 of the pawl element will engage the rail 11 so that further counterclockwise rock of the hand grip will then cause the pawl element to rock clockwise with respect to its own pivot 37 but evidently the amount of such return rock will necessarily be less than might be permitted by the spacing between the rails 10 and 11.

The structures so far described are also shown in my aforesaid earlier patent, No. 2,000,962, and they have been explained herein to enable a better exposition of my present improvements.

I have provided a spring element, 39, conveniently in the form of a wire spring element, but evidently other forms of spring may be used, to conform to the requirements which I shall now explain. This spring element includes the spiral portion 40 which sets over the rivet pivot 29, and the spiral portion 41 which sets over the rivet pivot 37. The lower end portion 42 of this spring element abuts against the right-hand edge portion of the bracket element 25 so as to provide an abutment for said lower end portion of the spring element; and the two spiral portions 40 and 41 are joined together by the central portion 43. The upper end portion 44 of the spring element is received through an opening 45 formed in the upper connecting portion 33 of the pawl element. The spring element as a whole is normally biased to cause the upper end portion 44 to tend to rock rightwardly about the rivet 29 as a pivot, the lower end portion 42 of the spring element being anchored or held stationary as explained. Under these conditions the following relationships and spring urgings are produced:

Due to the relationship of the pivot rivets 37 and 29 with respect to the anchored lower spring end 42 there is always a tendency to shift the pivot rivet 37 leftwardly, thus normally urging the hand grip to its leftward or non-operated position. Due to the spring bias of the spring element, there is a tendency or urging of the pawl element 30 to rock the same clockwise on the pivot rivet 37, such tendency existing at all times, both when the hand grip is in its leftward position of Figure 2 and also when it is in its most rightwardly rocked position of Figure 4. Due to this constant urging exerted on the pawl element it is evident that in the absence of suitable provision to limit clockwise rock of the pawl element about the pivot rivet 37 the right-hand edge 34 of said pawl element would always be retained in engagement with the teeth or serrations of the rail 10. However, I have provided a limit stop on the hand grip element to limit the amount of such clockwise rocking of the pawl element with respect to the hand grip. The stop thus provided comprises the lug or off-set portion 46 which is struck inwardly from the lug 24 (towards the observer when looking at Figure 4), or leftwardly when looking at Figure 6, the amount of such off-set being approximately the thickness of the flange of the pawl element or slightly more. This stop is so located that as the hand grip rocks counterclockwise under urge of the spring element, and to

wards the normal or un-operated position of such hand grip, said stop picks up the pawl element shortly before the hand grip completes its leftward rock, and carries the pawl element far enough to cause the edge portion 34 to effectively clear the teeth or serrations of the rail 10. Thus, when the hand grip stands in its spring returned position (shown in Figure 2) the pawl has been effectively cleared from the teeth or serrations, so that back and forth sliding movements of the carriage may be executed without interference between the pawl and the rail 10. Also, the left-hand edge portion 36 of the pawl element engages the rail 10 shortly after the pawl element has cleared the teeth or serrations, thus limiting the counterclockwise rocking movement of the hand grip.

When the hand grip is manually forced rightwardly or clockwise on its rivet pivot 29 the pawl element will continue to remain against such stop element 46 until finally the edge 34 of the pawl element comes into engagement with the rail 10, and engages one of the teeth thereof. Further clockwise rock of the hand grip will then occur with the stop element 46 moving downwardly from the pawl element, leaving the pawl element spring pressed against the rail 10 and its tooth or serration. Such condition is well shown in Figure 4.

On the return movement of the hand grip, after completing a jar cover removing operation, the spring urge of the spring section 41 will retain the pawl in engagement with the rail 10 until the stop 46 rises high enough to engage the edge of the pawl element. Thereafter further counterclockwise rock of the hand grip will cause said stop to force the pawl element to follow the movement of the hand grip, thus drawing the pawl edge 34 away from the rail 10 and its teeth and serrations, sufficiently to permit the carriage to be shifted freely up and down along the rails, as already explained.

With the spring improvements herein disclosed it is evident that after a jar cover removing operation has been executed, bringing the hand grip element to such a position as that shown in Figure 4, and with the carriage shifted along the rails, the hand grip may be relaxed to a greater or less extent, rocking counterclockwise about the rivet pivot 29, under urging of the spring element; and if, under these conditions the carriage be retained in its thus advanced position, the pawl edge 34 will be drawn downwardly into position to engage a more advanced tooth or serration of the rail 10. Then by another gripping movement on the hand grip a further advancement of the carriage may be executed beyond its previous position. Thus, if it should be found that the first gripping movement of the hand grip was not sufficient to bring about good engagement with the jar cover, such second hand grip movement would bring about the degree of engagement needed to enable the jar cover to be loosened and removed.

It will also be apparent that this spring arrangement ensures that the hand grip and the pawl element will always be in proper relative positions to permit a jar cover removing operation to be executed without any special adjustments of these parts by the operator, other than sliding the carriage along the rails far enough to bring the gripping edges 14 and 19 into good engagement with the jar cover flange at opposite sides thereof.

In Figures 5 and 7 I have shown a fragmentary 75

portion of a jar cover to which the cap remover of the present invention is to be engaged. This is the jar cover 47. It includes the usual straight flanged portion 43, shown as being knurled, and the threaded portion 49 which threads onto the threaded neck of the jar. The dimension of the straight section 43 is usually small, and present tendencies are towards reduction of the dimension of this straight section. It is desired that the jaws of the present utensil shall directly engage this straight section, and not the threaded section 49, since when such threaded section is engaged by the jaws, and said jaws are clamped firmly towards each other, it frequently happens that the threads are thus mutilated, and frequently they are even deformed sufficiently to clamp them against the material of the jar neck. When this happens the cover is itself thus clamped with increased firmness onto the jar neck, so that the difficulty of removing the jar cover is increased by the very implement which is intended to make the cover removal easier. It will be evident, however, that by ensuring that the engagement of the jaws shall always be made with the straight section 43 of the cover, the danger of deformation of the cover threads will be practically eliminated. It is desirable to form the jaw elements with some displacement between the plane which they occupy and the plane which includes the two arms 10 and 11, and such a displacement is shown in Figures 5 and 7. This displacement may be great enough to allow the undesirable engagement of the jaws with the cover threads 49. I have therefore made provision for ensuring jaw engagements with the covers in a plane closer to the plane of the arms 10 and 11 than that plane which includes the jaws 13 and 18. I shall now explain this feature:

40 The carriage element 15 is provided with one or two openings 50 and 51 at opposite sides of the ear perforation 28. I have shown in Figures 8 and 9 an insert 52 including the flat portion 53 adapted to set flat against the surface of the carriage plate 15, the separated lugs 54 and 55 which set at the sides of the ear 26, and the off-set flange portion 56 which terminates in the serrated edge 57. The amount of off-set of this portion 56 is less than the off-setting of the portion 18 of the carriage proper, but the serrations 57 of the insert are so formed that they align generally with the corresponding serrations 19 of the carriage jaw. The lugs 54 and 55 are provided with the ears 58 and 59 adapted to set through the openings 50 and 51, respectively, after which said ears may be riveted to the carriage plate to securely lock the insert in place.

60 Examination of Figure 5 will show that when such insert is provided the carriage has, in effect, two sets of serrated jaw elements in alignment with each other, so that the one or the other will surely engage the straight section 43 of the jar cover. Such engagement will be ensured, even though the other serrated jaw lie opposite to the threads of the jar cover. This is true since said threads are not of diameter, measured from the jar axis, greater than the diameter of the straight section 43 of the jar cover.

I have also shown, in Figure 7, an insert element 68 set between the cross member 12 and the flange 13 which comprises the stationary jaw element of the utensil. This insert is shown as being of sufficient thickness to completely fill the space between said cross member 12 and said flange 13, being tightly clamped between these

parts to hold the insert securely in place. This insert, when used, is also provided with serrations aligning with the serrations 14 of the flange and comprising, in effect, continuations of said serrations. Accordingly, this stationary jaw member will also grip the straight portion of the jar cover, and will not grip the threads thereof.

I claim:

1. In a jar cover remover, the combination of a frame element including a pair of parallel rails, 10 a carriage slidably mounted on said rails and including runners slideable on said rails and a cross member connected to said runners, a lever member including a hand grip located substantially in the plane of the parallel rails and outside of the frame element and rockable to a cover gripping position substantially parallel to the adjacent frame rail and said lever member including a pair of spaced apart elongated lugs lying parallel to said cross member, said elongated lugs being located between the parallel rails of the frame element and extending lengthwise of the jar cover remover, a first lever pivot pin secured to said carriage cross member substantially midway between the parallel rails and extending through the end portions of said spaced apart lugs, a pawl element located between the spaced apart lugs of the lever member and including a pair of spaced apart flanges lying parallel to the cross member, a second pawl pivot pin extending through the spaced apart lugs of the lever member at a location between the first pivot pin and the hand grip of the lever member and also extending through the spaced apart flanges of the pawl element, a pawl tooth on said pawl element extending towards the proximate surface of the frame rail most removed from the hand grip, together with a unitary elongated spring element having one end in engagement with the pawl

5 element at a point between the pawl pivot pin and the pawl tooth, and having its other end in engagement with the carriage cross member at a point adjacent to the lever pivot pin, said spring passing both the pawl pivot pin and the lever pivot pin and being in engagement with the pawl pivot pin at the pawl tooth side thereof, and being in engagement with the lever pivot pin at the hand grip side thereof, said spring acting to urge the pawl in a direction to move the pawl tooth towards the surface of the proximate frame rail and acting to urge the pawl pivot pin towards the other frame rail to thereby urge the lever member in a direction to move the hand grip 15 away from the frame rail which is adjacent to said hand grip.

2. A jar cover remover as specified in claim 1, together with co-operating means on the lever member and the pawl element located in position to limit rocking movement of the pawl element tooth towards the proximate surface of the frame rail prior to engagement of said pawl tooth with said rail surface when the hand grip is in lever 20 spring moved position most removed from the adjacent frame rail.

FRANZ K. KRAG.
